2,144,058

BANK FEEDING MECHANISM FOR PAPER FEEDING MACHINES

Henning Hallstream, Braintree, Mass., assignor, by mesne assignments, to Dexter Folder Company, Pearl River, N. Y., a corporation of New York

Original application April 21, 1937, Serial No. 138,119. Divided and this application November 4, 1937, Serial No. 172,728

6 Claims. (Cl. 271—62)

This invention relates to bank feeding mechanism for paper feeding machines and has for its object the improvement of the control of such mechanism. The subject matter of this application has been divided from my application, Serial No. 138,119, filed April 21, 1937.

In the drawings—

Figure 1 is a side elevation of a sheet separating and feeding machine operating with a fanned out bank of sheets.

Figure 2 is a plan view of the same machine, with the loader board removed, with parts broken away and parts omitted.

Figure 3 is a side elevation of the bank feed mechanism, with a part of the side plate broken out for clearness of illustration.

Figure 4 is a section on the line 4—4 of Figure 2.

Figure 5 is a plan view of one side of the bank feed mechanism.

At the top of the machine shown in Figure 1 is a loader board 2 over which travel loader belts 4 trained over rollers 6 and 8 (Figure 2). The roller 6 is mounted on bearing blocks 10 secured to the forward end of the loader board, while the roller 8 is mounted upon a shaft 12 journaled in side plates 14. A loader gauge 16 is provided to align the paper initially upon the loader board 2. Between the side plates 14 is a reversing throat of well-known form, represented by a guide 18, one end of which appears above the side plates in Figure 1. A crank handle 20 is secured to a shaft 22, the opposite end of which bears a pinion 24 meshing with a gear 26 fixed to shaft 12. By rotating the crank handle 20 from time to time the roller 8 is revolved to feed a bank of paper resting on the loader board 2 in preliminarily fanned out condition down through the reversing throat 18, which further fans out the bank.

The paper is received from the reversing throat by a bank feed table 28, over which travel bank feed belts 30 trained over rollers 32 and 34. The rollers 32 are mounted upon a shaft 36 journaled in bearing blocks 38 attached to the rear end of bank feed table 28. The rollers 34 are mounted on a shaft 40 journaled in bearings 42 at the forward end of the bank feed table. The shaft 40 is rotated intermittently by the mechanism now to be described, to feed forward the bank of paper resting upon the table 28 and belts 30.

At the left side of the machine there is pivoted upon shaft 40 a rocker arm 44, which carries on a pin 46 a pivoted pawl 48 engaging with

the teeth 50 of a ratchet wheel 52, which is fixed to shaft 40. The pawl is held against the ratchet wheel by a spring 54 stretched between a pin 56 on the pawl and a pin 58 on the rocker arm 44. The pawl bears a nose 60 which can be grasped to pull the pawl back from contact with ratchet wheel 52, throwing spring 54 above the center of pin 46, so that the pawl comes to rest in an inoperative position against a pin 62 projecting from the face of rocker arm 44. The rocker arm 44 is intermittently rocked by a driving mechanism mounted between two side plates 64 and 66 at the front end of the machine. On a stationary shaft 68 projecting inward from side plate 64 is pivotally mounted a rock lever 70 having a slot 72 in its rear end in which engages a bolt 74 of a link 76 connected by a bolt 78 with rocker arm 44. The forward end of lever 70 is connected by a pin 80 to the lower end of a spring 82, the upper end 20 of which is hooked over a stationary pin 84 on side plate 64. The lever 70 has a hub 86 from which projects a rigid arm 88 bearing a pin 90 which pivotally supports a roller 92. This roller bears against a cam 94 fixed to a shaft 96, which is revolvably mounted in bearings in side plates 64 and 66. The shaft 96 is rotated by a driving mechanism to be described later and cam 94, with the cooperation of spring 82, causes lever 70 to rock and oscillate the rocker arm 44, thus turning ratchet wheel 52 by pawl 48 and feeding forward the bank of paper.

The feed of the bank of paper is not continuous, but is interrupted when the leading edge of the bank reaches a certain position at the forward end of the bank feed table. The interruption of the feed of the bank may be effected by a feeler mechanism now to be described.

At the forward end of the bank feed table 28 there extends across the machine between the side plates 64 and 66 a shaft 98, which carries lower delivery rolls 100. Upper drop rolls 102 are mounted upon swinging arms 104 supported on a shaft 106 pivotally mounted in the side plates 64 and 66. The delivery rolls 100 and 102 receive the paper from the sheet separating mechanism to be described later. On shaft 98, near the center line of the feeder, there is mounted a bracket 108, which has a depending arm 110 recessed to fit over stay bolt 112, and a rearwardly extending arm 114 provided with a bearing 116 embracing a shaft 118, which is mounted between the side plates 64 and 66. The feeler mechanism includes a trip lever 120

mounted at the center line of the feeder upon a pivot 122 on bracket 108. In addition to its paper engaging arm this lever 120 has a stop arm 124 and a weight arm 126 tending to tip it toward the right (Figure 3). The upper end of the stop arm is positioned so as to lie under the end of an arm 128 clamped to a shaft 130 pivotally mounted in the side plate 64 and bracket 108. The shaft has fixed to it another arm 132 connected at its end to a rod 134. The upper end of rod 134 is connected at 136 to a lever 138 pivoted upon a shaft 140 mounted between the arms of a bracket 142. The bracket is fixed by set screw 144 upon a stay bolt 146 mounted between the side plates 64 and 66. The outer end of lever 138 bears a roller 148, which rides upon a cam 150 mounted upon drive shaft 96. Lever 138 has an arm 152 extending to the left, the end of which is articulated to a rod 154 guided for vertical movement in a hole in the bottom plate of bracket 142. A compression spring 156 surrounding rod 154 tends to rotate lever 138 clockwise, so that its roller 148 constantly rides upon cam 150. The hub 158 of lever 138 has a cam finger 160, which bears against a cam finger 162 of a lever 164 pivotally mounted on a shaft 166 extending across the arms of bracket 142. This lever is held against cam finger 160 by a spring 168 connected at its opposite end to a pin 170 on lever 138. Lever 164 has a downwardly extending arm 172 which cooperates with the outer end of arm 88 to interrupt the rocking motion of that arm at times. The mechanism just described operates in the following manner:—

Assuming the paper feed mechanism to be in operation, that is, the arm 44 rocking and stepping the ratchet wheel 52 forward, the bank of paper will be advanced until the leading edge of the bank comes against trip lever 120 and moves it to the left, from its dot and dash line position of Figure 3 to its full line position. This motion swings stop arm 124 to the left and allows arm 128 to rock downward and to the full line position, and rod 134 to descend as roller 148 rides onto the lower part of cam 150. The downward movement of rod 134 and lever 138 attached thereto causes cam finger 160 to swing to the left against cam finger 162, moving the lower arm 172 of lever 164 over the end of lever 88 blocking its movement. Thus the lever 88 is prevented from following cam 94 and the rocking motion of arm 44 is stopped. When paper has been removed from the bank sufficiently to allow trip lever 120 to return to the normal position shown in dot and dash lines, the stop arm 124 prevents downward movement of rod 134 and consequently the lever arm 172 remains out of the path of lever arm 88, which is then free to execute its rocking movements under the control of cam 94. The forward feed of the paper is thus resumed and it will be evident that the mechanism will operate in such a way that there will be little variation in the position of the top sheet of the bank of paper.

Means for picking up and feeding forward the top sheet of the bank of paper and driving means for operating such means are well known in the art, and, not being herein claimed per se, are not herein fully described or illustrated. Figures 1 and 2 may therefore be considered as showing, in addition to parts of the bank feed mechanism above described, essential parts of any known or preferred form of mechanism for separating the top sheet from the pile and forwarding it to the feed-off rolls 100, 102. The general features of

such mechanism on one side of the machine are shown at A and a like structure is implied at B but not illustrated. One of the telescoping shafts 546 transmits motion from the drive shaft 96 to sheet separating and forwarding means operating on the rear edge of the pile, including, as here indicated, combing wheel 572 for buckling the top sheet or sheets of the pile, the sucker gripper 286 oscillating about a shaft 282 for picking up the sheet and forwarding it to feed-off rolls, and suitable suction and blast nozzles and air and vacuum tubes and controlling valves timed to apply partial vacuum or winding air-pressure as required by the special form of these well-known mechanisms which is adopted. So far as such parts are here shown they correspond with those exhibited in the original application of which this is a division, but any known form which will successively present the sheets to the feed-off rolls, may be used.

To prevent the sheet of paper which is being fed forward after separation from the bank from riding upon the top of finger 120 and holding the finger toward the left, thus interfering with the normal control of the bank feed, there is provided a finger guard 174 pivoted at 176 on bracket 108 and normally held by a spring 178 attached to its arm 180 so that its upper hooked end 182 overhangs the top of finger 120 and provides a support upon which the paper can glide as it moves into the delivery rolls 100, 102. If the finger guard 174 should remain constantly in its full line position, the leading edge of the paper might become hooked under its end 182. To prevent this the guard is momentarily swung to the left to its dot and dash line position, where its end 182 is within the periphery of delivery roll 100. For this swinging motion the guard is provided with an arm 184 resting upon an actuating arm 186 fixed upon a shaft 188, which is pivoted between side plate 64 and bracket 108 directly under shaft 130. Another arm 190 fixed to shaft 188 is connected by a rod 192 to a lever 194 which is similar to lever 138, being pivotally supported on shaft 140 and provided at its outer end with a roller 196 which rides upon a cam 198. The roller is pressed against the cam by a spring 200 surrounding guide rod 202 attached at 204 to the left end of lever 194 and guided for vertical movement in a hole in the bottom plate of bracket 142. The cam 198 is designed to raise lever 194 a moment before the paper begins its forward movement after separation (the drive of this cam being synchronized with that of the sheet separating mechanism), and to hold the lever in its elevated position, with guard 174 swung to the left, until the paper has entered the delivery rolls 100, 102. The guard 174 is then restored by spring 178 to its normal position over finger 120.

I claim:

1. In a machine for separating sheets of paper, a bank feed table, means for feeding a fanned out bank of paper along said table, means for blocking the operation of the feeding means, a cam, a follower therefor, means controlled by said follower for operating the blocking means to stop the operation of said feeding means, a trip finger projecting into the path of the leading edge of the bank of paper, and means controlled by said finger for withholding said follower from said cam and unblocking the operation of the feeding means.

2. In a machine for separating sheets of paper, a bank feed table, means for feeding a fanned out bank of paper along said table comprising an actuating arm operated by a spring in one direc-

- tion and by a cam in the opposite direction, a second cam, a follower therefor, a stop movable by said follower into the path of said actuating arm to prevent it from being moved by said spring, a trip finger projecting into the path of the leading edge of the bank of paper, and means controlled by said finger for withholding said follower from said second cam.
3. In a machine for separating sheets of paper, a bank feed table, means for feeding a fanned out bank of paper along said table, delivery rolls, means including a trip finger in position to be engaged by the advancing front edge of the bank of paper for controlling the feed of the bank, and a guard normally extending over the top of said finger having means for moving it away from such position timed to operate immediately before the paper enters the delivery rolls.
4. In a machine for separating sheets of paper, a bank feed table, means for feeding a fanned out bank of paper along said table, means including a trip finger in position to be engaged by the advancing front edge of the bank of paper for controlling the feed of the bank, means for picking up and feeding forward the top sheet of the bank of paper, driving means for said last means, a movable guard normally extending over said trip finger, and means operated by said driving means for intermittently removing said guard in synchronism with the pick-up and feed of the paper.
5. In a machine for separating sheets of paper, a bank feed table, means for feeding a fanned out bank of paper along said table, actuating means for said feeding means, means for interrupting said actuating means including a cam, a follower for said cam, a spring urging said follower against said cam, a stop device connected with said follower, and a trip device normally holding said stop device and preventing said follower from following said cam, said trip device being movable by the advancing edge of the bank of paper to release said stop device.
6. The combination with delivery rolls, of means for feeding sheets thereto, comprising a bank feed table, means for feeding a fanned out bank along said table toward said delivery rolls, means for interrupting the operation of said bank feeding means comprising a trip device at the end of said bank feed table adjacent said delivery rolls, a movable guard normally overhanging said trip device, and means for withdrawing said guard within the periphery of one of the delivery rolls.

HENNING HALLSTREAM.
